METHOD OF MAGNETIC CORE CONSTRUCTION

Oliver G. Attewell, South Milwaukee, Wis., assignor to
McGraw-Edison Company, a corporation of Delaware

Filed Nov. 13, 1956, Ser. No. 621,629

7 Claims. (Cl. 29—155.61)

This invention relates to stationary induction apparatus and in particular to a method of constructing magnetic cores for stationary induction apparatus.

This application is a continuation-in-part of my application Serial No. 303,232 entitled "Core for Electromagnetic Induction Apparatus," filed August 8, 1952, now U.S. Patent No. 2,942,218, and having the same assignee as the present invention.

Although wound magnetic cores of continuous strip material having a preferred direction of grain orientation lengthwise thereof are ideal in that they provide minimum exciting current and minimum core loss, such continuous strip cores cannot be disassembled for repair in the field in the event an electrical winding fails. In order to permit disassembly of laminations of a wound core from a preformed electrical winding it is well known to construct a magnetic core by cutting through a wound closed loop and to reverse alternate turns to interleave the ends of the turns and provide two sets of circumferentially spaced butt joints. My aforementioned application discloses that cutting through a wound strip loop in a long diagonal and reversing alternate turns in stacking to dispose the butt joints formed by the diagonally cut ends opposite substantially uncut portions of adjacent laminations results in a core having remarkably low exciting current and core loss. However, the laminations of cores constructed by this method of cutting through a single core and reversing alternate turns do not always interfit as tightly and compactly as desirable, and it may be necessary to apply mechanical force to hold the lamination ends in butt-jointed relation. This is particularly true when long diagonal cuts are made through the core and alternate turns are reversed so that the diagonal butt joints in adjacent layers cross. With this arrangement a lamination end cut at an obtuse angle meets a lamination end cut at an acute angle in each turn at two corners of the core, and relatively large air gaps, as well as undesired openings where the joints cross, may result unless means are provided to hold the lamination ends in butt-jointed relation.

It is an object of the invention to provide a novel method of constructing magnetic cores having laminations which can be assembled to and disassembled from a preformed winding which substantially overcomes the aforementioned difficulties inherent in a method including the steps of cutting through a single wound core and reversing alternate turns. It is a further object of the invention to provide such an improved method of constructing magnetic cores which results in air gaps of minimum spacing between the cut lamination ends.

Other objects and advantages of the invention will be apparent from the following description when taken in conjunction with the accompanying drawing wherein:

FIG. 1 is a view in perspective illustrating the steps of the method of the invention wherein two similar closed loops are wound and long diagonal cuts are made through the loops at circumferentially spaced apart points;

FIG. 2 is an exploded perspective view illustrating the method steps of concentrically stacking certain turns from each of the loops of FIG. 1 to construct a closed magnetic core;

FIG. 3 is an exploded perspective view illustrating an alternative stacking of the turns;

FIGS. 4 and 5 illustrate steps of an alternative form

2

of the method wherein right angle cuts are made through two similar loops and certain turns from each of the loops are reassembled to form a closed magnetic core;

FIGS. 6 and 7 illustrate another form of the method wherein cuts are made through both legs of each closed loop; and

FIGS. 8 and 9 illustrate still another form of the method of the invention wherein both wound loops are cut at the same place.

10 The present invention is a continuation-in-part of my copending application Serial No. 303,232, now U.S. Patent No. 2,942,218, which discloses and claims a magnetic core having a long diagonal butt joint construction which provides considerably lower joint reluctance, core loss, and exciting current than prior art cores having laminations which may be assembled to and disassembled from a preformed winding. The novel method of the present invention overcomes certain aforementioned shortcomings of the method and magnetic core claimed in application Serial No. 303,232, and in accordance with the preferred embodiment of the present invention illustrated in FIG. 1 two similar closed, convoluted, four-sided loops 10 and 11 are spirally wound from magnetic strip material having a direction of easiest magnetization lengthwise thereof. Preferably the magnetic ribbon for winding the two loops 10 and 11 is of approximately the same width and is wound to approximately the same number of turns. Preferably the winding is on a rectangular mandrel (not shown) to form the four-sided closed loops 10 and 11, although the winding can be on a circular mandrel and the wound turns shaped to rectangular configuration prior to annealing.

35 In accordance with the preferred embodiment of the invention, cuts are made through the loops 10 and 11 at circumferentially spaced apart points 13 and 14. The cuts may be made by a saw or a thin abrasive cutting wheel rotating at high speed. As shown the cuts are made through what may be considered "opposite" legs 15 and 16 of the two loops 10 and 11, but it will be appreciated that the method of the invention embraces the cutting of the two loops at circumferentially spaced apart points irrespective of whether one loop is cut in a winding leg and the other loop is cut along a yoke or whether the cuts are made at circumferentially spaced apart points 40 through the same side of both loops. Inasmuch as the results of any previous annealing step are apt to be at least partially destroyed by cutting, the loops are preferably annealed after the cuts are made at points 13 and 14, although the invention contemplates making the cuts 45 at 13 and 14 subsequent to annealing.

50 As illustrated in FIGS. 1 and 2, each of the cuts at 13 and 14 is along a diagonal having a length greater than $\sqrt{2}$ times the width of the magnetic strip. In the final

55 core the butt joints between such diagonally cut lamination ends are disposed opposite substantially uncut surfaces of adjacent laminations. The reluctance of a butt joint is a function of the amount of magnetic material in the portion of the adjacent layer opposite the joint.

60 The magnetic flux density is equal in a layer having a butt joint and in a layer adjacent thereto, and with a right angle butt joint substantially all the magnetic flux transfers to the portion of the adjacent layer opposite the joint and this portion saturates when the magnetic flux density in other portions of the core is only approximately fifty

65 percent of saturation density. This crowding of flux in the adjacent layer produces local saturation with the result that the reluctance of such a right angle butt joint is relatively high and there is a marked increase in exciting current required to produce the total magnetic flux, the value of which is fixed by the voltage of the apparatus.

70 In the preferred embodiment the length of diagonal cuts

at 13 and 14 is such that the portion of the adjacent lamination opposite the joint does not saturate prior to other portions of the core and consequently joint reluctance and exciting current are minimized. This improved result is attained in the preferred embodiment of the invention by making cuts through loops 10 and 11 having lengths greater than $\sqrt{2}$ times the width of the magnetic strip material. If the butt joints are of a length twice the width of the magnetic strip, the amount of magnetic material in a cross section through the adjoining layer along the line of the butt joint is equal to the area of magnetic material in a radial cross section through both the layer having the butt joint and the adjoining layer. My aforementioned application Serial No. 303,232, now U.S. Patent No. 2,942,318, includes graphs illustrating the marked reduction in exciting current and core loss resulting from the increased length of butt joint and reference is made thereto for details of the improved results.

The loops 10 and 11 while held in quadrangular shape are subjected to a strain-relief anneal in an inert or other suitable gaseous atmosphere. The annealing step removes the deleterious strains introduced in the oriented magnetic material by the winding and cutting operations and permanently sets the turns in the shape they are held during annealing.

The turns formed by cutting the closed loops 10 and 11 at points 13 and 14 are then reassembled to form two closed magnetic cores in each of which turns from loop 10 are adjacent turns from loop 11 and the butt joint between the respective ends of each turn is opposite a substantially uncut portion of an adjacent turn. This circumferential spacing of the butt joints in adjacent turns assures that the flux crossover at all the joints does not occur in the same portion of the core and thus local saturation is avoided.

In accordance with the illustrated method of the invention certain turns from each of the loops 10 and 11 are concentrically stacked to construct one magnetic core and the remaining laminations are concentrically stacked to construct a second magnetic core. The turns of only one of the two magnetic cores is shown in the exploded perspective view of FIG. 2 wherein it is illustrated that radially inward turn 28 of the final core is the radially inward turn of loop 11. The turn 21 radially outward from turn 20 in the magnetic core is from loop 10 and comprises the second turn radially outward from the window therein. The next radially outward turn 22 of the magnetic core is also from loop 10 and comprises the third radially outward turn therein which is reversed 180 degrees before stacking. The fourth lamination 23 radially outward from the core window is from loop 11 and is reversed 180 degrees before stacking. This sequence of stacking to position turns from loop 11 adjacent turns from loop 10 is repeated until a first closed magnetic core is constructed, and the remaining turns from loop 10 and the remaining turns from loop 11 are concentrically stacked in a similar pattern to form a second magnetic core with turns from loop 10 adjacent turns from loop 11 and with the ends of each turn meeting end to end opposite an uncut portion of both adjacent turns.

In the alternative form of the invention illustrated in FIG. 3 loops 10 and 11 are constructed as illustrated in FIG. 1, and odd-numbered laminations from loop 11 are concentrically stacked with even-numbered laminations from loop 10 to construct a first closed magnetic core, and the remaining even-numbered turns from loop 11 are stacked with the remaining odd-numbered turns from loop 10 to construct a second closed magnetic core. Only one of the two magnetic cores constructed by this method of the invention is represented in the drawing, and as shown radially inward turn 20 of the magnetic core is the radially innermost turn of loop 11. Turn 21 radially outward from turn 20 of the magnetic core is from loop 10 and comprises the second turn removed from the window

therein. The next radially outward turn 24 of the magnetic core is from loop 11 and comprises the third turn removed from the window therein. The fourth turn 25 radially outward from the core window is from loop 10. In this manner odd-numbered turns from loop 11 and even-numbered turns from loop 10 are concentrically stacked into a closed magnetic core with the turns from loop 11 adjacent the turns from loop 10 and with the respective ends of each turn meeting end to end opposite uncut portions of both adjacent laminations. In a similar manner the remaining even-numbered turns from loop 11 are concentrically stacked with the remaining odd-numbered turns from loop 10 to form a second closed magnetic core.

In the method of the invention illustrated in FIGS. 4 and 5, two substantially identical loops 10 and 11 are wound as described above, but right angle cuts are made at circumferentially spaced apart points 43 and 44 through the same yoke of both loops 10 and 11. One 20 final core illustrated in FIG. 5 may be constructed by stacking odd-numbered turns 50, 52 etc. from one loop, e.g. loop 10, with even-numbered turns 51, 53 etc. from the second loop 11. As illustrated in FIG. 4 a right angle cut is made at 43 through the top yoke 45 of loop 10 at a 25 place to the left of the midpoint thereof, and a right angle cut is made at 44 through the top yoke 46 of core 11 at a place to the right of the midpoint thereof. After the two loops are annealed to preset the turns in desired quadrangular shape, a final core shown in FIG. 5 is constructed 30 with the radially inward turn 50 thereof being the radially innermost turn of loop 10. The turn 51 of the magnetic core radially outward from turn 50 is the second turn radially outward from the window of loop 11. The third turn 52 of the magnetic core is the third turn radially 35 outward from the winding window of loop 10, and the next outward lamination 53 of the magnetic core is the fourth lamination radially outward from the window of loop 11. This procedure of stacking is repeated until a magnetic core having the desired number of turns is 40 built up. In a similar manner the remaining even-numbered turns from loop 10 are stacked with the remaining odd-numbered turns from loop 11 to construct a second magnetic core.

In the alternative method of the invention illustrated in FIGS. 6 and 7, cuts are made through both winding legs of each of two identical wound loops 10 and 11 constructed in a manner described above. Long diagonal cuts are made at 63 and 65 through the winding legs of loop 10, and similar long diagonal cuts, but at angles 50 complementary to cuts 63 and 65, are made at 64 and 66 through opposed legs of loop 11. A first magnetic core is then constructed by stacking odd-numbered turns 70, 72 etc. from one loop, e.g. loop 11, with even-numbered turns 71, 73 etc. from the second loop, e.g. loop 10. In 55 the first magnetic core the radially innermost turn 70 comprising laminations 80 and 81 is from loop 11, and the next radially outward turn 71 comprising laminations 83 and 84 is from loop 10. The next outward turn 72 of the first magnetic core is from loop 11 and comprises laminations 85 and 86 having their diagonally cut ends in butt-jointed relation. The fourth turn 73 radially outward from the core window is from loop 10. This pattern of stacking is repeated until a first magnetic core is completed, and the remaining odd-numbered turns from 60 loop 10 and the remaining even-numbered turns from loop 11 are stacked in a similar manner to construct a second magnetic core.

It will be appreciated that although the preferred embodiment of the invention has been illustrated and described as including the step of cutting loops 10 and 11 at circumferentially spaced apart points, it is within the spirit and scope of the invention to cut both loops 11 and 10 at the same place, e.g. at 89 as shown in FIG. 8, and to reassemble odd-numbered turns 90, 92 etc. from one 65 loop, e.g. loop 11, with even-numbered turns 91, 93 etc.

5 from the other loop 10 by reversing the turns from one of the loops (as shown in FIG. 9 the turns 91, 93 etc. from loop 10 are reversed) to construct a first closed magnetic core wherein the ends of each turn meet end to end opposite a substantially uncut portion of an adjacent turn. In a similar manner a second closed magnetic core is constructed by concentrically stacking the even-numbered turns from loop 11 with the odd-numbered turns from loop 10 to position the butt joints opposite uncut portions of adjacent turns.

In cores constructed in accordance with the method of the invention, it is unnecessary to force the lamination ends into butt-jointed relation. The laminations interfit relatively compactly, the air gap spacing between lamination ends is a minimum, and no relatively wide openings occur where the diagonal joints of adjacent laminations cross as sometimes resulted in cores constructed in accordance with the method of my application Serial No. 303,232 unless means were provided to force the lamination ends into butt-jointed relation.

While only a few alternative methods in accordance with the invention have been illustrated and described, many modifications and variations of the invention will be apparent to those skilled in the art, and it is intended in the appended claims to cover all such modifications and variations as fall within the true spirit and scope of the invention.

I claim:

1. The method of constructing magnetic cores for stationary induction apparatus, comprising the steps of winding magnetic strip material flatwise to form a four-sided closed convoluted structure, winding magnetic strip material flatwise to form a second four-sided closed convoluted structure substantially identical in size to said first structure, making a cut through one side of said first structure of a length greater than the $\sqrt{2}$ times the width of the magnetic strip material and making a cut through one side of said second structure at a place differing from that at which said first structure is cut and of a length greater than the $\sqrt{2}$ times the width of said magnetic strip material, whereby each structure includes a plurality of turns of progressively different peripheral length, disassembling the turns of both of said structures and reassembling in order of progressively different peripheral length given whole turns from said first structure and given whole turns from said second structure with the ends of each turn meeting end to end opposite a substantially uncut portion of an adjacent turn and with turns of said first structure adjacent turns of said second structure to form a first closed magnetic core, and reassembling in order of progressively different peripheral length the remaining whole turns from said first structure and the remaining whole turns from said second structure with the ends of each turn meeting end to end opposite a substantially uncut portion of an adjacent turn and with turns of said first structure adjacent turns of said second structure to form a second closed magnetic core.

2. The method of constructing magnetic cores for stationary induction apparatus, comprising the steps of winding magnetic strip material flatwise to form a first four-sided closed convoluted structure, winding magnetic strip material flatwise to form a second four-sided closed convoluted structure substantially identical in size to said first structure, making a long diagonal cut through one side of said first structure of a length greater than the $\sqrt{2}$ times the width of said magnetic strip material, making a long diagonal cut through one side of said second structure of a length greater than the $\sqrt{2}$ times the width of said magnetic strip material, the cuts being in the same side of both structures but extending in opposite directions, strain-relief annealing said first structure and said second structure to preset the turns thereof in four-sided configuration, disassembling the turns of both of said structures and concentrically stacking in order of pro-

gressively different peripheral length given whole turns from said first structure and given whole turns from said second structure with turns of said first structure adjacent turns of said second structure and with the diagonally cut ends of each turn meeting end to end to form a long diagonal butt joint and with the butt joints of adjacent turns crossing to form a first closed magnetic core, and concentrically stacking in order of progressively different peripheral length the remaining whole turns of said first structure and the remaining whole turns of said second structure with turns of said first structure adjacent turns of said second structure and with the diagonally cut ends of each turn meeting end to end and forming a long diagonal butt joint and with the butt joints of adjacent turns crossing each other to form a second closed magnetic core.

3. The method of constructing magnetic cores for stationary inductance apparatus, comprising the steps of 20 winding magnetic strip material flatwise to form a first four-sided closed convoluted structure, winding magnetic strip material flatwise to form a second four-sided closed convoluted structure substantially identical in size to said first structure, cutting through one side of said first structure, cutting through one side of said second structure at 25 a place differing from that at which said first structure is cut, disassembling the turns of both of said structures and concentrically stacking in order of progressively different peripheral length odd-numbered whole turns from said first structure and even-numbered whole turns from said second structure into a closed magnetic core with the respective ends of each of said turns meeting end to end opposite a substantially uncut portion of an adjacent turn, and concentrically stacking in order of progressively different peripheral length the even-numbered whole turns 30 from said first structure and the odd-numbered whole turns from said second structure into a second closed magnetic core with the respective ends of each turn meeting end to end opposite a substantially uncut portion of an adjacent turn.

4. The method of constructing magnetic cores for stationary induction apparatus, comprising the steps of winding magnetic strip material flatwise to form a first four-sided closed convoluted structure, winding magnetic strip material flatwise to form a second four-sided closed convoluted structure substantially identical in size to said first structure, cutting through at least one side of said first structure, cutting through at least one side of said second structure at a place differing from that at which said first structure is cut, disassembling the turns of both 45 of said structures and reassembling in order of progressively different peripheral length given whole turns from said first structure and given whole turns from said second structure into a first closed magnetic core with the turns of said first structure adjacent turns of said second structure and with the respective ends of each turn meeting end to end opposite a substantially uncut portion of an adjacent turn, and reassembling in order of progressively different peripheral length the remaining whole turns from said first structure and the remaining whole turns from 50 said second structure into a second closed magnetic core with the turns from said first structure adjacent turns from said second structure and with the ends of each turn meeting end to end opposite a substantially uncut portion of an adjacent turn.

5. The method of constructing magnetic cores for stationary inductance apparatus, comprising the steps of 55 winding magnetic strip material flatwise to form a first four-sided closed convoluted structure, winding magnetic strip material flatwise to form a second four-sided convoluted structure substantially identical in size to said first closed structure, cutting through one side of said first structure, cutting through one side of said second structure at a place differing from that at which said first structure was cut, strain-relief annealing said first structure and said second structure to preset the turns thereof

in four-sided configuration, disassembling the turns and concentrically stacking in order of progressively different peripheral length given whole turns from said first structure with given whole turns from said second structure so that the respective ends of each of said turns meet end to end opposite a substantially uncut surface of an adjacent turn and with turns from said first structure adjacent turns from said second structure to form a first closed magnetic core, and concentrically stacking in order of progressively different peripheral length the remaining whole turns from said first structure with the remaining whole turns from said second structure so that the ends of each turn meet end to end opposite a substantially uncut portion of an adjacent turn and with the turns from said first structure adjacent turns of said second structure to form a second closed magnetic core.

6. The method of constructing magnetic cores for stationary induction apparatus, comprising the steps of winding magnetic strip material flatwise to form a first four-sided closed convoluted structure, winding magnetic strip material flatwise to form a second four-sided closed convoluted structure substantially identical in size to said first structure, making a cut through one side of said first structure of a length greater than the $\sqrt{2}$ times the width of said magnetic strip material, making a cut through one side of said second structure of a length greater than the $\sqrt{2}$ times the width of said magnetic strip material at a place differing from that at which said first structure is cut, disassembling the turns of both of said structures and concentrically stacking in order of progressively different peripheral length odd-numbered whole turns from said first structure and even-numbered whole turns from said second structure into a closed magnetic core with the ends of each turn meeting end to end opposite the substantially uncut portion of an adjacent turn, and concentrically stacking in order of

progressively different peripheral length the even-numbered whole turns of said first structure and the odd-numbered whole turns of said second structure into a second closed magnetic core with the ends of each of said turns meeting end to end opposite a substantially uncut portion of an adjacent turn.

7. In the method of constructing magnetic cores for stationary induction apparatus, the improvement comprising the steps of providing two substantially equal size, four-sided, closed, convoluted annealed loops of flatwise wound magnetic strip having a permanent set of four-sided configuration, cutting through the convolutions of one of said loops to provide whole turn laminations each having a single joint therein and cutting through the convolutions of the second of said loops at a place circumferentially offset from the place of cutting of the first of said loops to provide whole turn laminations each having a single joint therein, and concentrically assembling odd-numbered whole turn laminations from said first loop with even-numbered whole turn laminations from said second loop into a closed magnetic core with the respective ends of each of said turns meeting end to end opposite a substantially uncut portion of an adjacent turn.
